UNITED STATES PATENT OFFICE.

MATTHEW CHAPMAN, OF GREENFIELD, MASSACHUSETTS.

DESIGN FOR A BOLSTER FOR TABLE CUTLERY.

Specification forming part of Design No. 5,543, dated February 20, 1872.

Specification describing a new and original Design for Table Cutlery, invented by MATTHEW CHAPMAN, of Greenfield, in the county of Franklin and State of Massachusetts.

The drawing represents a side view of a knife made according to my design.

This invention relates to a new form of metallic bolster for the handles of knives and forks; and consists in making them with a long shank, equally shaped in cross-section, as the handle proper, and provided with a projecting grooved flange.

A in the drawing represents the handle, B the bolster, C the blade of a knife.

The bolster has a shank, *a*, proportionately longer than those formerly used, even with the handle, as shown. It also has a flange, *b*, grooved at the edge.

The invention is equally applicable to forks as it is to knives.

I claim as my invention—

The design for a bolster for table cutlery, as shown.

MATTHEW CHAPMAN.
